(57) **CLAIM**

The ornamental design for a hidden corner pantry for recreational vehicle, substantially as shown and described above.

DESCRIPTION

FIG. 1 shows a top plan view of a portion of an RV incorporating the design of the present invention, with the diagonal wall closed over the pantry portion to conceal the pantry when access to the pantry is not needed. The portions of the RV not adjacent the pantry and diagonal wall form no portion of the claimed design and are illustrated in dashed line format. The remaining contents and features of the RV form no portion of the claimed design and are omitted from this figure for clarity.

FIG. 2 shows a top plan view of the design of the present invention according to the embodiment of FIG. 1, with the diagonal wall opened to allow access to the pantry portion; and,

FIG. 3 shows an isometric upper, front, right view of the design of the present invention according to the embodiment of FIG. 1.

The broken lines shown illustrate portions of the hidden corner pantry for recreational vehicle and environment that form no part of the claimed design.
